UNITED STATES PATENT OFFICE.

GEORGE H. WILLIAMSON, OF JERSEY CITY, NEW JERSEY.

TOY.

1,216,195.

Specification of Letters Patent. Patented Feb. 13, 1917.

Application filed May 2, 1916. Serial No. 94,956.

To all whom it may concern:

Be it known that I, GEORGE H. WILLIAMSON, a citizen of the United States, residing at Jersey City, in the county of Hudson and State of New Jersey, have invented new and useful Improvements in Toys, of which the following is a specification.

This invention relates to toys and has for its principal object the provision of a device of this character which will be instructive, educational and amusing; one which may be readily converted from a portable wheeled structure of one design to other portable structures of many designs, each of a mechanical formation which will permit of its sustaining the weight of a child and capable of being propelled over the surface of the ground.

With the above and other objects in view which will appear as the nature of the invention is better understood, the same consists in the improved construction and novel arrangements of parts which will hereinafter be fully described and particularly pointed out in the claims.

In the accompanying drawings, has been illustrated, a single and preferred form of the invention, it being, however, understood, that no limitations are necessarily made to the precise structural details therein exhibited, but that changes, alterations and modifications within the scope of the claims may be resorted to when desired.

In the drawings:

Fig. 1, is a side view of the device set up in the form of a two wheeled cart.

Fig. 2, is a bottom plan view of a portion thereof.

Fig. 3, is a side view of the device showing the same set up in the form of a four wheeled wagon.

Fig. 4, is a bottom plan view of the forward portion thereof.

Fig. 5, is a side view of the device showing the same converted into a still further form of vehicle, one adapted to be propelled by the foot of the operator.

Fig. 6, is a side view of another form of the device simulating a bicycle which is adapted to be used when coasting down grade.

Fig. 7, is a top plan view thereof.

Fig. 8, is a bottom plan view of a portion of the same.

Fig. 9, is a section taken on the line 9—9 of Fig. 7.

Fig. 10, is a perspective view of the seat.

Fig. 11, is a side view of the device converted into another form of vehicle such as a wheelbarrow.

60

Fig. 12, is a bottom plan view thereof.

Fig. 13, is a view illustrating the number of the mechanical elements used in forming the device.

Fig. 14, is a perspective view of the front axle when the device is set up in wagon form, as shown in Fig. 3.

Fig. 15, is a perspective view of one of the end boards as used in Fig. 3.

In carrying the invention into practice, use is made of a number of stock mechanical elements all or a part of which constituting one of the many portable structures to be hereinafter specifically referred to. These elements are simple in design and are adapt-

ed to be assembled with one another for the completion of the object to be formed without requiring any extended skill of mechanics. Therefore, the device may be set up and knocked down and converted from a

structure of one design to a structure of a totally different design by the inexperienced mind of a child. The device nevertheless, contains many educational features in that the various elements constituting the same

may be technically catalogued and the training afforded a child in setting up the many different objects is quite material and beneficial, saying nothing of the enjoyment and pleasure which may be had through the use

of the different forms of structures as they are set up by the child. I have as far as is practicable, used a set of mechanical elements in which almost the same elements

will be employed when changing the device from a structure of one type to a structure of a different type.

In the form shown in Fig. 1, the same being a two wheeled cart, use is made of a platform 1, two diverging reach bars 2—2, 100 an axle 3, having wheels 4—4, and a pole 5. At the front end, where the reach bars come together, a small clip 6, is used which is bolted at 7, beneath the said reach bars and as shown, said pole is extended through the eye 8, of the clip and the rear end which is provided with spaced plates 9—9, is arranged over a removable block 10, under the reach bars and a bolt 11, is then passed through the platform 1, and through the block 10, and a small metal cross piece 12,

which extends over the plates 9—9. In ad-

UNITED STATES PATENT OFFICE.

OTTO WINKLER, OF CÖPENICK, AND RUDOLF URTEL, OF NIEDER-SCHÖNEWELDE, GERMANY, ASSIGNORS TO GENERAL ELECTRIC COMPANY, A CORPORATION OF NEW YORK.

VALVE-GEAR FOR INTERNAL-COMBUSTION ENGINES.

1,216,196.

Specification of Letters Patent. Patented Feb. 13, 1917.

Application filed March 13, 1912. Serial No. 683,476.

To all whom it may concern:

Be it known that we, OTTO WINKLER, a subject of the King of Prussia, residing at Cöpenick, Germany, and RUDOLF URTEL, a subject of the King of Prussia, residing at Nieder-Schöneweide, Germany, have invented certain new and useful Improvements in Valve-Gears, for Internal-Combustion Engines, of which the following is a specification.

This invention relates to internal combustion engines, and its object is to utilize the pressure of the expanding gases in the cylinder to assist in the movements of the valve gear. The operation of opening the outlet passage in such engines must be effected very rapidly, necessitating extreme acceleration in the movement of the valve and its gearing. By causing the pressure of the exploding charge to act upon this valve, the mechanism which operates it is assisted and greater promptness of operation is secured. To this end we use an annular valve located inside the cylinder and actuated by a rod or stem passing out through a stuffing box in the head of the cylinder. The inlet and outlet ports or passages are both controlled by this one valve, the arrangement being such that the outlet passage is opened when the valve stem moves outwardly from the interior of the cylinder and the inlet port when the valve moves inwardly.

The accompanying drawing is a diagrammatic section of a cylinder of an internal combustion engine, showing our improved construction of the valve.

The cylinder 1 has an outlet or exhaust port 2 located below the plane of the inlet or fuel admission port 3. The annular slide 40 valve 4 controls both ports, and is actuated by the stem 5 which passes out through an opening in the head 6 of the cylinder. In practice, this opening is of course provided with a suitable stuffing box or packing. When the charge has been fired, the pressure in the combustion chamber between the head 6 and the piston 7 acts upon the cross sectional area of the stem 5 and tends to lift the valve thereby assisting the valve mechanism in effecting a quick uncovering of the outlet port 2. Moreover, when the suction stroke of the piston occurs, the atmospheric pressure on the outer end of the stem aids the valve mechanism in opening the inlet port. To state the matter in an-

other way the valve is balanced except as to its stem so that when a difference in pressure exists between the inside and outside of the cylinder, the said valve tends to move toward the region of lower pressure under 60 a force represented by the area of the valve stem times the said pressure difference. Inasmuch as this force is first in one direction and then in the other, it assists first in opening the fuel port 3 and later in opening 65 the exhaust port 2.

With this arrangement, therefore, the movements of the valve in each direction are effected in part positively by the valve mechanism and in part automatically by the 70 unbalanced fluid pressures on the valve and its stem.

We have not illustrated the mechanical means for moving the valve since any suitable mechanism for the purpose may be employed and further because it seems unnecessary to an understanding of the invention. To enable the invention to be more readily understood, the moving and stationary parts have been separated by relatively 75 80 large clearances. In practice these parts make, of course, a good working fit.

In accordance with the provisions of the patent statutes, we have described the principle of operation of our invention, together 85 with the apparatus which we now consider to represent the best embodiment thereof; but we desire to have it understood that the apparatus shown is only illustrative, and that the invention can be carried out by other 90 means.

What we claim as new and desire to secure by Letters Patent of the United States, is:

1. The combination with an internal combustion engine, of a valve located inside the cylinder thereof and controlling both the inlet and outlet ports, and means for operating said valve both positively and by the unbalanced fluid pressures on the valve including a part extending out through the end of the cylinder toward which the valve moves to open the outlet port and away from which end it moves to open the inlet port.

2. The combination with an internal combustion engine, of a valve located inside the cylinder thereof and controlling both the inlet and outlet ports, and a valve stem passing through the head of the cylinder and ex-
